WRENCH FOR NAIL POLISH BOTTLE CAPS

Edwin H. Holtz, Poland, Ohio, assignor to Turn-a-Cap Inc., Damascus, Ohio, a corporation of Ohio

Filed Nov. 6, 1963, Ser. No. 77,314

Term of patent 7 years

(Cl. D54—16)

I claim:

The ornamental design for a wrench for nail polish bottle caps, as shown.
